UNITED STATES PATENT OFFICE.

HARRY J. HICK, OF ALLIANCE, OHIO, ASSIGNOR TO THE McCASKEY REGISTER COMPANY, OF ALLIANCE, OHIO, A CORPORATION OF OHIO.

FILING APPLIANCE.

1,086,770.

Specification of Letters Patent. Patented Feb. 10, 1914.

Application filed June 5, 1912. Serial No. 701,794.

To all whom it may concern:

Be it known that I, HARRY J. HICK, a citizen of the United States, residing at Alliance, in the county of Stark and State 5 of Ohio, have invented certain new and useful Improvements in and Relating to Filing Appliances, of which the following is a specification.

This invention relates to filing appliances 10 adapted for the receiving and holding of papers, bills and the like and permitting their ready and accurate filing, inspection and removal.

For the purpose of illustration, I have, 15 in the accompanying drawings, shown and herein described one form of apparatus embodying my invention.

Figure 1 is a side elevation, partly broken away, of a filing appliance embodying my 20 invention. Fig. 2 is a fragmentary side elevation, somewhat enlarged, of the appliance. Fig. 3 is a fragmentary bottom plan view of the holders. Fig. 4 is a perspective view of the bearing on which the front end holder is 25 supported.

In the drawings, 1 indicates a casing of suitable size and shape and having a support 1^a and a back 1^b. The support 1^a is extended forwardly, as shown at 1^c, to provide a suitable rest for the holders as will 30 presently be set forth. Below the support 1^a and rest 1^c, the casing may be constructed to form an inclosure 1^d to receive one or more sliding trays 1^e.

2 indicates a series of holders, comprising a front end holder 2^a, a rear end holder 2^b and intermediate holders 2^c, adapted to be assembled face to face in a substantially upright position as shown in Fig. 1. Each of the 35 holders 2^c is preferably formed from sheet metal to form a back 2^d. This back may be extended and pressed or bent into a hollow hinge bar 2^e that extends from end to end of the back.

45 2^f indicates spacing and partition strips fixed to the opposite faces of the backs 2^d in a well known manner.

50 2^h indicates the paper holding devices or clips, preferably formed from sections of resilient wire and fixed to the backs 2^d in any suitable way. Each device 2^h is preferably provided with a plate 2^{h'} for display-

ing an eye-signal or index character which indicates what papers are to be filed under the adjacent clip.

55

The end holders 2^a, 2^b, are constructed like the holders 2^c, except that they are provided with partitions 2^f and holding clips 2^h on their inner faces only and are provided with auxiliary plates 2^{h'} on their outer faces 60 to make a complete and neat appearance to the series of holders.

3 indicates as a whole pivotal connections between the holders 2, these connections operating to connect the holders together and 65 permitting them to swing relatively to each other from a substantially vertical position to a substantially horizontal position, and vice versa. The holders may be operated singly or in groups in either direction.

70

The pivotal connections between the holders 2 preferably comprise connectors 3^a and pintles 3^c which pivotally connect the connectors together. The connectors may be fixed to the hinge bars 2^e of the holders 2 75 in any convenient manner and provided with depending bearing plates 3^b in which are formed suitable bearing openings to receive the pintles 3^c. As will be understood from the drawings, the front end holder 2^a, 80 and each alternate holder is provided with two spaced connectors 3^a, and each of the remaining holders is provided with one connector 3^a that is disposed between the connectors 3^a on the adjoining hinge bar or bars 2^e. 85 This construction and arrangement is the preferred one since each pintle has bearing support on one holder on opposite sides of its connection with the adjoining holder.

The pintles are all headed at one end, as 90 shown at 3^d, while their opposite ends may be split to form wings 3^e which are distorted as shown in Fig. 3, permitting the removal of the pintle and detachment and attachment of the holders one relative to the 95 other; or all of the pintles 3^c except one may be upset, as shown at 3^f.

I preferably construct the pintle 3^c between the rear end holder 2^b and adjoining holder 2^c with wings 3^e in order to permit the detachment of the 100 rear holder 2^b and the insertion of additional holders 2^c, as shown in dotted lines in Fig. 3.

4 indicates a pivot bearing for the series of holders 2. This bearing is mounted on

the support 1^a and is adapted to removably receive a pintle 3^c, carried at the forward ends of the connectors 3^a for the front holder 2^a, whereby it serves as the pivot bearing for the front holder 2^a and those holders which may be operated therewith at any one time. It coöperates with the back 1^b, or a cushion device 5 carried by said back, to support the holders in their normal position. The bearing 5 is adjustable on the support 1^a relative to the back 1^b, in order to provide for the increase or decrease in the number of holders utilized at any time.

The bearing 4 preferably comprises a plate 4^a arranged transversely of the support 1^a and a bearing member 4^b mounted on and adjustable to different positions along said plate 4^a. The plate 4^a is formed with a series of openings 4^c spaced from each other equal distances. At its forward end it may be provided with lateral members 4^d which are secured in a well known manner to the support 1^a. The bearing member 4^b is preferably formed from a section of metal bent or otherwise shaped to form a transverse cavity or pintle seat 4^b, standards 4^e and feet 4^f. The feet 4^f are provided with devices 4^g which extend into the openings 4^c and lock the bearing member 4^b to the plate 30 in any position desired. The devices 4^g may consist of screws extending through openings formed in the feet 4^f and arranged to enter the support 1^a (see dotted lines in Fig. 2), whereby the bearing member will be 35 firmly held in its adjusted position.

6 indicates a device for guiding the rear end holder in its up and down movements. This device is preferably pivoted on the back 1^b and may be provided with a latch 40 6^a at or near its front end. When the holders are being operated the guide 6 assumes the position indicated in dotted lines in Fig. 1 and guides the rear holder. When the holders are returned to normal position, 45 the device 6 falls by gravity into engagement with the upper ends of the holders, with the latch 6^a in front of the front holder 2^a, whereby it operates to lock all of said holders against operation.

50 While I have described herein but one set of connections 3 and one bearing member 4 therefor, it will be understood that in the practical embodiment of the invention I prefer to provide two sets of connections 3 and 55 two bearings 4 arranged near the opposite ends of the holders 2.

My invention permits the adaptation of 60 the filing appliance by the increase or decrease of the number of holders to the conditions and requirements to which it may be subjected at any time, that is to say, where larger and increased filing capacity is required, one end holder may be detached and supplemental holders added to the series; 65 also, where the conditions are such that the

70 filing spaces or sections on all the holders are not being used, the unused holders may be detached. This arrangement is advantageous since, as will be clearly understood, the reduction of the number of holders will result in permitting them to be operated with greater speed and less physical effort.

75 In the ordinary use of the invention, the merchant is originally supplied with a sufficient number of holders to carry his accounts, and as his business increases from time to time, he may provide for such increase by the addition of supplemental holders, thus obviating the heavy expense of 80 purchasing a second appliance or a new one of large size. When four holders, for example, are added at the rear of the series, the bearing member 4^b is adjusted forwardly, or away from the back 1^b, to the position shown in dotted lines in Figs. 1 and 2.

85 When the supplemental holders are added or holders removed, the bearing member 4^b is adjusted along the plate 4^a according to the position of the front end holder 2^a so as to coöperate with the back 1^b to support the 90 holders 2 in a substantially upright position.

95 The removable pintle 3^c may be provided between any two adjoining holders 2, but since the clips 2^h are preferably numbered *seriatim*, the lowest ones being on the front end holder 2^a, I prefer to provide it between the rear end holder 2^b and adjoining holder 2^c, so that when the supplemental holders are added, the clips 2^h thereon may be properly numbered *seriatim*.

100 When the number of holders 2 are changed, the guide 6 is preferably removed and a new one of proper length substituted.

To those skilled in the art of making filing appliances of the class described, many 105 alterations in construction and widely differing embodiments and applications of my invention will suggest themselves, without departing from the spirit and scope thereof.

110 My disclosures and the description herein are purely illustrative, and are not intended to be in any sense limiting.

What I claim is:

1. In a filing appliance, the combination 115 of a casing, a series of holders having pivot connections between them, the connections between two of said holders being detachable, and an adjustable bearing for one of the end holders arranged to be positioned in the casing to support said end holder 120 when the number of holders is increased or diminished.

2. The combination with a casing having a support and a back, of an adjustable bearing mounted on said support, and a series 125 of holders having connections between them, the connections between two of said holders being detachable, the said bearing forming a support for the front end holder of the series of holders and coöperating with the 130

back to support the front holder and the remaining holders in upright position according to the number of holders in the series.

3. The combination with a casing having
5 a support, of a series of holders arranged
to be assembled face to face on said support
normally in upright position, and an adjustable bearing for the front end holder of
said series of holders, the said bearing
10 comprising a member formed to provide a bearing recess, standards and feet and means
for securing said feet to said support.
4. The combination with a casing having
a support, of a series of holders arranged to
15 be assembled face to face on said support

normally in upright position, and an adjustable bearing for the front end holder of
said series of holders, the said bearing comprising a plate formed with a series of
aligned openings, a bearing member formed
20 to provide a bearing recess, standards and
feet and means on said feet and extending
through said openings in the plate to secure
the bearing member thereon.

In testimony whereof I affix my signature, 25
in the presence of two witnesses.

HARRY J. HICK.
